US00D978564S

(12) **United States Design Patent** (10) Patent No.: **US D978,564 S**
 Wang et al. (45) Date of Patent: **** Feb. 21, 2023**

(54) **PILLOW**

(71) Applicant: **TAIZHOU SUNJOY CAR ACCESSORIES CO., LTD.**, Zhejiang (CN)

(72) Inventors: **Ronghua Wang**, Zhejiang (CN); **Youfu Tan**, Zhejiang (CN); **Aili Ding**, Zhejiang (CN)

(73) Assignee: **TAIZHOU SUNJOY CAR ACCESSORIES CO., LTD.**, Taizhou (CN)

(**) Term: **15 Years**

(21) Appl. No.: **29/769,168**

(22) Filed: **Feb. 3, 2021**

(51) LOC (14) Cl. **06-13**
 (52) U.S. Cl. **USPC D6/601**

(58) **Field of Classification Search**

USPC D6/595, 596, 601, 604; D24/183, 190;
